(57) **CLAIM**

The ornamental design for a packaging liner, as shown and described.

DESCRIPTION

FIG. 1 is a top perspective view of a first embodiment of a packaging liner, showing our new design;

FIG. 2 is a top plan view of the packaging liner shown in FIG. 1;

FIG. 3 is a bottom plan view of the packaging liner shown in FIG. 1;

FIG. 4 is a left-side elevation view of the packaging liner shown in FIG. 1;

FIG. 5 is a right-side elevation view of the packaging liner shown in FIG. 1;

FIG. 6 is a front elevation view of the packaging liner shown in FIG. 1;

FIG. 7 is a rear elevation view of the packaging liner shown in FIG. 1;

FIG. 8 is a perspective view thereof, shown in a position of use with an exemplary package and two exemplary packaging liners;

FIG. 9 is a top perspective view of the packaging liner shown in FIG. 1, shown with a portion of the top ply removed to show aspects of the design not visible when combined;

FIG. 10 is a top perspective view thereof, shown with a portion of the top ply, as well as a portion of a top interior layer, removed to show aspects of the design not visible when combined;

FIG. 11 is a top perspective view of a second embodiment of a packaging liner, showing our new design; and,

(Continued)

FIG. 12 is a top perspective view thereof, shown with a portion of the top ply, as well as a portion of a top interior layer, removed to show aspects of the design not visible when combined.

The evenly broken lines are shown for the purpose of illustrating both parts of the article as well as environmental subject matter of an exemplary packaging container and exemplary packaging liners. None of the broken lines forms part of the claimed design. The packaging liner is shown with symbolic breaks in its length and width. The appearance of any portion of the packaging liner between the break lines forms no part of the claimed design. Thin diagonal shade lines and grey are used to show a reflective surface.
